TARGET GAME CASING

Feodor Keosiff, 11306 Culver Blvd., Culver City, Calif.

Filed Dec. 27, 1960, Ser. No. 63,342

Term of patent 3½ years

(Cl. D34—5)

FIG. 1.

FIG. 2.

FIG. 3.

FIG. 4.

FIG. 5.

FIG. 6.

FIG. 1 is a front elevational view of the target game casing showing my new design;

FIG. 2 is a rear elevation of the casing;

FIG. 3 is a side elevation thereof looking toward the left side of FIG. 2;

FIG. 4 is a side elevation looking toward the right side of FIG. 1;

FIG. 5 is a top plan view thereof; and,

FIG. 6 is a bottom plan view thereof.

I claim:

The ornamental design for a target game casing, substantially as shown.
